FIG. 7.

UNITED STATES PATENT OFFICE.

PETER DEVLIN, OF BALTIMORE, MARYLAND, ASSIGNOR OF ONE-HALF TO
J. C. MCKENNIE, OF CHARLOTTESVILLE, VIRGINIA.

STOPPER-FASTENING.

SPECIFICATION forming part of Letters Patent No. 645,352, dated March 13, 1900.

Application filed June 26, 1899. Serial No. 721,921. (No model.)

To all whom it may concern:

Be it known that I, PETER DEVLIN, a citizen of the United States, residing at Baltimore, in the State of Maryland, have invented certain new and useful Improvements in Stopper-Fastenings; and I do hereby declare the following to be a full, clear, and exact description of the invention, such as will enable others skilled in the art to which it appertains to make and use the same.

My invention relates to improvements in stopper-fasteners for bottles, jars, and the like; and it consists in the novel device hereinafter described and claimed.

Reference is had to the accompanying drawings, wherein the same parts are indicated by the same letters throughout the several views.

Figure 1 represents an elevation of a bottle-neck fitted with one form of my improved stopper-fastener. Fig. 2 is a similar view taken at right angles to the view shown in Fig. 1. Fig. 3 is a section taken on the line 3 3 in Fig. 2. Fig. 4 is a view similar to Fig. 1, showing another form of lock-strip. Fig. 5 is a section taken on the line 5 5 in Fig. 4 looking in the direction of the arrow. Fig. 6 is a sectional view, and Fig. 7 is a top plan view showing a modified form of the holding-cap.

Referring to Figs. 1, 2, and 3, A represents a disk of thin metal having opposite lugs A', provided with openings a' near their ends. The disk and its integral lugs A' are preferably stamped from a sheet or strip of metal, the said disk being given the form of a shallow cap to fit over the upper end of the stopper B. The length of the lugs A' depends upon the depth of the usual boss C upon the mouth of the bottle-neck C', the openings a' in said lugs being so located that when the cap or disk A is fitted upon the stopper, the latter being seated in the bottle-neck C' and the said lugs bent down along the exterior surface of the bottle-neck, said openings will lie opposite the usual contraction c at the base 45 of the boss C, as shown. In this position the said lugs may be engaged for locking the fastener by a band of wire D encircling the neck of the bottle at the base of the boss C. This band of wire is provided with a tongue d at 50 one side, formed by bending a short portion of the wire strip back upon itself, as seen in Fig. 2. After encircling the bottle-neck the ends of this wire strip are brought together

upon the opposite side from the tongue d and a similar tongue d' is formed, the said tongues 55 extending radially from opposite points on the surface of the bottle-neck. The tongues d and d' so formed may engage in the openings a' of the lugs A', the said tongues being afterward bent downward to retain the said 60 lugs, as seen in Figs. 1, 2, 3, and 6 of the drawings.

Instead of a wire band D a band of sheet metal, such as shown at E in Figs. 4 and 5, may be used, the said band being applied in 65 the same manner; but the tongues e and e' thereof for engaging the lugs A' of the cap are flattened or spread to secure the same, as seen in Fig. 5.

The cap or disk may be solid, as seen in 70 Figs. 1 to 4 at A, or may be made of an annular form with a central opening, as shown at A⁰ in Figs. 6 and 7, to admit a corkscrew, or, if preferred, for any other reason.

The solid caps A may conveniently have 75 some distinctive mark indicative of the nature of the contents of the vessel or the manufacturer's mark stamped thereon if desired.

Having thus described my invention, what I claim, and desire to secure by Letters Patent of the United States, is—

1. In a stopper-fastener, the combination with a disk to fit upon the stopper, provided with radially-disposed flexible lugs having openings therethrough; of a separate metallic strip to encircle the bottle-neck, having tongues formed by lapping portions thereof, arranged to engage the openings in said lugs, substantially as described.

2. In a stopper-fastener, the combination with a disk to fit upon the stopper, provided with oppositely-disposed flexible lugs having openings therethrough; of a band to encircle the bottle-neck composed of a bent metallic strip having tongues formed by lapping portions thereof, said tongues being arranged to engage the openings in said lugs when the parts are applied to the bottle, substantially as described.

In testimony whereof I affix my signature 100 in presence of two witnesses.

PETER DEVLIN.
